UNITED STATES PATENT OFFICE.

LEON P. EARL, OF CINCINNATI, OHIO, ASSIGNOR TO THE AROMINT COMPANY, OF CINCINNATI, OHIO, A CORPORATION OF OHIO.

DESIGN FOR A DISPLAY AND DISPENSING DEVICE.

51,723.

Specification for Design.

Patented Feb. 5, 1918.

Application filed August 18, 1917. Serial No. 187,026. Term of patent 3½ years.

To all whom it may concern:

Be it known that I, LEON P. EARL, a citizen of the United States, residing at Cincinnati, in the county of Hamilton and State of Ohio, have invented a new, original, and ornamental Design for Display and Dispensing Devices, of which the following is a specification, reference being had to the accompanying drawing, forming part thereof.

The figure is a perspective view of a display and dispensing device illustrating my new design.

I claim:

The ornamental design for a display and dispensing device, substantially as shown.

LEON P. EARL.
